UNITED STATES PATENT OFFICE.

ALBERT AUGUST WEBER, OF SAN FRANCISCO, CALIFORNIA.

CAR-AXLE BOX.

SPECIFICATION forming part of Letters Patent No. 564,856, dated July 28, 1896.

Application filed July 27, 1895. Renewed June 13, 1896. Serial No. 595,498. (No model.)

To all whom it may concern:

Be it known that I, ALBERT AUGUST WEBER, a citizen of the United States, and a resident of San Francisco, in the county of San Francisco and State of California, have invented certain new and useful Improvements in Car-Axle Boxes; and I do declare the following to be a full, clear, and exact description of the invention, such as will enable others skilled in the art to which it appertains to make and use the same, reference being had to the accompanying drawings, and to figures of reference marked thereon, which form a part of this specification.

15 Figure 1 is a central vertical section through car-axle box with invention applied thereto, brush and actuating parts being shown in full. Fig. 2 is a section on line *x x*, Fig. 1. Fig. 3 is a section on line *y y*, Fig. 1, cap-20 plates 17 and 18 removed. Fig. 4 is a front view of one of yokes. Fig. 5 is a similar view of the other yoke. Fig. 6 is a rear view of yoke shown in Fig. 5. Fig. 7 is a plan view of axle-box, cap-plates, and top spring 20 removed. Fig. 8 is a perspective view of cap-25 plates fastened. Fig. 9 is a perspective view of box-cover.

This invention is designed to provide a dust-proof car-axle box; and it consists in the 30 novel construction and combination of parts, all as hereinafter described, and pointed out in the appended claims.

Referring to the accompanying drawings, the numeral 1 designates a car-axle box having therein a lubricant-chamber 2 and a brass or bearing 3 for the car-axle 4. 5 is the cover of said box, which is formed at its upper edge with a beveled inclined flange 6, which engages over a beveled rib or flange 7 on the 40 top of said box. Near the lateral edges of the cover on its inner face are secured strips 7^a, which fit neatly within the opening in the end of the box, while the marginal portions 8 outside of said strips seat neatly upon the 45 inclined ends of the lateral walls of said box. Between said strips 7^a, near the bottom edge of the cover, is a transverse strip 9, whose lower edge is beveled, as shown at 10, to form with the cover a seat to receive and fit closely 50 the bottom beveled edge 11 of the opening in the box. The object in view in the above-described construction of the cover is to se-

cure a perfectly close fit which will prevent dust from entering the box and the lubricant from escaping therefrom.

55

The inner end of the box is formed at its lateral edges with the projecting flanges 12, which form between them a seat for a gasket or packing device of the construction now to be described. This gasket consists of two 60 plates or yokes 13 of similar form, having each the approximately semicircular bearing 14 and block 15 secured thereto. These two plates 13 are applied to each other reversely, the arms of one piece fitting neatly the lateral 65 edges of the block 15 of the opposite piece, with the two semicircular bearings 14 uniting to form a complete bearing which is designed to fit neatly the axle 4.

16 designates two springs, which are secured 70

one to the face of the yoke piece or plate 13 nearest the car-wheel and the other to the block 15 of the other of said pieces or plates.

These springs are engaged by the sliding cap-75

pieces 17 and 18 to press the two plates or pieces 13 into close contact with each other and with the seat. 19 designates similar

springs, which are placed at the lateral edges of the gasket and against the inner faces of the flanges 12. 20 is a spring which is se-80

cured to the upper edge of one of the yoke pieces or plates 13 and which is engaged by the horizontal flange 23 on the upper edge of the cap-plate 17 to hold said piece or plate in

close contact with the axle. Said cap-plates 85

are formed at their lateral edges with guide-ways 21, which slide upon ribs or guides 22 of the flanges 12. Each of said plates is cut away at 22^a to fit the axle, and the said flange

23 of the upper plate 17 fits over a dust-strip 90

23^a, secured to or formed on the top of the box.

24 designates suitable fastening devices, by means of which said plates 17 and 18 are secured to each other.

95

25 designates a lubricating-brush whose shaft 26 is journaled to rotate in lugs 26^a of a slotted plate or bracket 27, which is fastened to the bottom of the box underneath the car-axle and its brass by means of a bolt

100 28, which engages the slot of the plate and is secured by a nut 29 upon the outside. On the outer end of the shaft 26 is fixed a ratchet-wheel 30.

31 is a lever which is fulcrumed at its lower end upon a pin or stud 32 of the plate or bracket 27, and whose upper portion has an elongated slot 33, which engages a wrist 34 on the end of the car-axle. Carried by a stud of said lever 31 is a pawl 35, which is held in engagement with the ratchet-wheel 30 by means of a spring 36. 37 is a gravity-pawl, which prevents said ratchet-wheel from turning backward.

It will be readily understood that the rotation of the car-axle will, through the wrist 34, actuate the lever 31 and pawl 35 to cause a step-by-step rotation of the brush 25. This brush takes up the lubricant in the chamber 2 and applies it to the surface of the car-axle, thus keeping the latter properly lubricated so long as any oil remains in the said chamber.

20 The feature of the slot, which is engaged by the bolt 28, not only permits the proper adjustment of the brush with relation to the axle-journal, but it also permits the bracket 27 to be moved endwise toward the outer end 25 of the box, where the brush-shaft can be lifted out of its bearings and a new brush put in. Inasmuch as the brushes become worn or unfit for use after some time, it is desirable to renew them, and were the bracket fixed under- 30neath the axle-journal it would not be an easy matter to do this through the opening in the outer end of the box; but by the provision of the slot this can be readily accomplished. The bracket may also be moved in this manner to permit more ready access to the pawls 35 should they become inoperative from any cause.

Having thus described my invention, what I claim as new, and desire to secure by Letters 40 Patent, is—

1. In a self-lubricating car-axle box, the combination with the box having the open-

ing in its inner end and the projecting flanges 12 at the lateral edges of said end, of the gasket or packing device seated between said flanges, and consisting of two similar plates or yokes 13, applied to each other reversely and cut away each to form an approximately semicircular bearing-opening 14 for the axle, and a block 15 secured to each of the said pieces and engaged by the cut-away portion of the opposite piece, the sliding cap-plates 17, 18, springs 16 seated between said cap-plates and the plates 13, springs 19 seated between the lateral edges of the said plates 13 and the flanges 12, and a spring 20 secured to the upper edge of one of the plates 13, and engaged by one of said cup-plates, substantially as specified.

2. In a dust-proof car-axle box, the combination with the box having an opening in its outer end, the lower edge of said opening having an outward and downward bevel, and a beveled rib 7 secured transversely across the upper edge portion of the said opening, 60 of the cover 5 for the said opening, said cover having on its upper edge a beveled, inclined flange 6 which engages over the beveled rib 7, and near each lateral edge a strip 7^a which fits within the said opening, and the transverse strip 9 which is secured to the lower inner portion of said cover between the strips 7^a, and which is beveled on its lower edge to form with the lower edge portion of the cover a seat or groove which receives the beveled 70 lower edge of the said opening, substantially as specified.

In testimony whereof I affix my signature in presence of two witnesses.

ALBERT AUGUST WEBER.
